Primary Examiner — Manpreet Matharu*Assistant Examiner* — Aula Soroush(74) *Attorney, Agent, or Firm* — Price Heneveld LLP(57) **CLAIM**

The ornamental design for a weighted bolero, as shown and described.

DESCRIPTION

FIG. 1 is a front elevation view of a weighted bolero showing our new design;

FIG. 2 is a rear elevation view thereof;

FIG. 3 is a left-side elevation view thereof;

FIG. 4 is a right-side elevation view thereof;

FIG. 5 is a top plan view thereof; and,

FIG. 6 is a bottom plan view thereof.

The broken lines in the drawings illustrate portion of the weighted bolero that do not form part of the claimed design.

1 Claim, 5 Drawing Sheets(56)
